SHOE HEEL

Edgar E. Joiner, Andover, Mass., assignor to Fred W. Mears Heel Company, Inc., Lawrence, Mass., a corporation of Massachusetts

Filed Apr. 14, 1961, Ser. No. 64,743

Term of patent 14 years

(Cl. D7—5)

Fig. 1

Fig. 2

Fig. 3

Fig. 4

FIG. 1 is a side view of a shoe heel showing my new design;

FIG. 2 is a rear view thereof;

FIG. 3 is a bottom view of the shoe heel; and

FIG. 4 shows the shoe heel in perspective as viewed from the front and the right side of the heel.

I claim:

The ornamental design for a shoe heel as shown.
